MERCOID SWITCH

John McArthur Harris, Jr., Baton Rouge, La.,
assignor to Standard Oil Development Com-
pany, a corporation of Delaware

Application September 14, 1935, Serial No. 40,575

1 Claim. (Cl. 200—112)

This invention relates to improvements in a switch of the type in which mercury is used to make and break connection between electrical conductors.

5 The invention will be fully understood from the following description taken in connection with the accompanying drawings, in which latter—

Fig. 1 is a longitudinal sectional view through 10 a preferred form of switch showing the plunger in its elevated position;

Fig. 2 is a longitudinal sectional view of the 15 device of Fig. 1 showing the plunger in its depressed position with the solenoid energized;

Fig. 3 is a longitudinal sectional view through 20 the device showing the solenoid in elevated position and the plunger held by the solenoid in elevated position; and

Fig. 4 is a longitudinal sectional view of the 25 device of Fig. 3 showing the plunger in its lowered position with the solenoid de-energized.

Referring particularly to Figs. 1 and 2 of the drawings the device comprises a sealed envelope having depending wells 3 and 4. The wells 3 and 4 contain a column of mercury 5 and 6 respectively. Alternatively, other electrical conductive liquid can be used instead of mercury and some of the advantages of the invention will be retained. Lead wires formed of tungsten or the like, and designated 8 and 9, pass through the walls of the wells 3 and 4 respectively in contact with the column of mercury contained therein.

A plunger 11 is mounted for vertical reciprocation within the envelope 1. The plunger comprises a float member 12 which is supported by the mercury 6 within the well 4. A magnetic member 13 is disposed within the plunger 11. The plunger 11 is preferably formed of glass, such as pyrex glass. A solenoid 16 having leads 40 17 encircles the envelope 1 in position, when activated, to draw the magnetic member 13 downwardly thereby immersing the float 12 within the mercury 6, as indicated in Fig. 2. This effects displacement of a portion of the mercury 6 causing the mercury to overflow into the well 3, thereby establishing electrical contact between the columns of mercury 5 and 6 by means of the connecting layer of mercury designated 20 in Fig. 2.

Means are provided for adjusting the switch 45 so that closing the circuit through the solenoid 16 will either close or open the switch. The means comprises a mercury reservoir 21 which opens into the envelope 1 above the wells 3 and 4, and which is provided with a body of mercury 50 designated 23. In the arrangement illustrated

in Figs. 1 and 2 the level of mercury in the well 4 is so adjusted that with the plunger 11 floating in the column of mercury 6, the level 24 of the column 6 is below the bottom wall 26 of the opening between the wells 3 and 4, so that there 5 is no electrical connection between the mercury columns 5 and 6 when the solenoid 16 is de-energized. The solenoid 16 is positioned slightly below the magnetic member 13, whereby when current is passed through the solenoid the 10 plunger is drawn down in the mercury 6 and the switch is closed, as illustrated in Fig. 2.

Referring particularly to Figs. 3 and 4 of the drawings, the device is illustrated with a portion of the mercury 23 within the mercury reservoir 15 21 poured into the well 4, leaving only a small volume of mercury 30 within the reservoir 21. In order to operate this form of the invention the solenoid 16 is elevated with respect to the magnetic member 13, so that when current is 20 passed through the solenoid 16 the plunger 11 is maintained in elevated position withdrawn from the column of mercury 6 within the well 4, as is illustrated in Fig. 3. In this position the level 24 of the column of mercury 6 is below the bottom wall 26 of the opening between the wells 3 25 and 4. Consequently there is no electrical contact between the columns of mercury 5 and 6.

On de-energizing the solenoid 16 the plunger 11 drops, partially submerging the float 12 within the column of mercury 6 and effecting over-flow of the column of mercury 6 into the well 3, causing a layer of mercury 20 to connect the columns of mercury 5 and 6, as previously described in connection with Figs. 1 and 2.

The plunger 11 and columns of mercury 5 and 6 are sealed in the pyrex glass shell 1, which has 30 previously been filled with moisture-free hydrogen gas at a pressure slightly below atmospheric pressure, such as 700 mm. pressure. The magnetic member 13 within the pyrex glass plunger is 35 preferably a soft iron core which is sealed into the plunger. Since the soft iron core is sealed into the plunger it is not necessary to de-gas the core when evacuating the envelope 1 preliminary 40 to filling the envelope 1 with hydrogen gas. Any oxygen retained in the iron core is prevented by the plunger from uniting with the hydrogen to 45 form water, which would corrode the iron and foul the surface of the mercury. Similarly, the 50 sealed iron core is prevented from getting in contact with the electric arc at the make and break of the circuit and small pieces of iron are 55 prevented from being knocked off into the mercury. Since the make and break is through the liquid

- there is no wearing away of the liquid surface caused by an electric arc. The construction described is relatively simple. It has no moving parts which are exposed. The device does not buzz when the solenoid is actuated by alternating current. There are no exposed metal parts which might be affected by corrosion. The atmosphere of hydrogen gas within the envelope is completely moisture-free.
- 5
- 10 Various changes and alternate arrangements may be made within the scope of the appended claim, in which it is my intention to claim all novelty inherent in the art as broadly as the prior art permits.
- 15 I claim:
- An electric switch of the liquid flow type comprising a sealed tubular envelope having depending wells communicating with each other through

the envelope, a column of mercury in each well, an electrode in each well in contact with the mercury, a plunger comprising a magnetic member enclosed in non-porous material and mounted for longitudinal movement in the mercury of one of the wells, a solenoid for effecting movement of the plunger whereby in one position the plunger is lowered displacing a portion of the mercury in the last-mentioned well to cause overflow of the mercury into the other well and establish an electric circuit through the columns of mercury between the electrodes, and a reservoir containing mercury communicating with the envelope whereby the quantity of mercury in the wells can be varied to either cause the plunger 10 to close the circuit by moving it into the well or by withdrawing it from the well.

CERTIFICATE OF CORRECTION.

Patent No. 2,103,459.

December 28, 1937.

JOHN McARTHUR HARRIS, JR.

It is hereby certified that error appears in the printed specification of the above numbered patent requiring correction as follows: In the grant, line 6, title of invention, for "MERCOID SWITCHES" read MERCURY SWITCHES; and in the heading to the printed specification and drawings, for "MERCOID SWITCH" read MERCURY SWITCH; and that the said Letters Patent should be read with these corrections therein that the same may conform to the record of the case in the Patent Office.

Signed and sealed this 1st day of March, A. D. 1938.

(Seal)

Henry Van Arsdale,
Acting Commissioner of Patents.
